UNITED STATES PATENT OFFICE.

ARTHUR KNEISEL, OF CLEVELAND, OHIO.

TEST-CONNECTOR FOR ELECTRIC WIRES.

1,244,099.

Specification of Letters Patent.

Patented Oct. 23, 1917.

Application filed November 27, 1911. Serial No. 662,569.

To all whom it may concern:

Be it known that I, ARTHUR KNEISEL, a citizen of the United States of America, and a resident of the city of Cleveland, county of 5 Cuyahoga, and State of Ohio, have invented certain new and useful Improvements in Test-Connectors for Electric Wires, of which the following is a specification.

My invention relates to improvements in 10 test-connectors for electric wires, and has for its object the provision of a connecting member which will be extremely simple in construction, while possessing the advantages of securing the maximum efficiency, coupled 15 with a low cost of production.

The principal utility of my improvement consists in mechanically and electrically connecting two or more wires carrying the electric current, such as telephone party line 20 wires, in an improved manner. Inasmuch as these devices commonly are used out of doors, the need for efficiency, simplicity and cheapness is obvious, since devices of this 25 character are required in very large numbers, and rarely ever are they used a second time.

Accordingly, I have devised several types of test-connector which are herein shown and described in typical forms, as embodiments of my said invention.

Referring to the drawings which I shall later describe in detail, it is seen that the test-connector comprises a common metallic strip or body-member in association with a 35 plurality of clips structurally adapted thereto and secured in place, preferably by screw-bolts. Either the body member or the clips are suitably formed to fit one within or upon the other, so as to hold these members in 40 proper relation and clamp the interposed wires firmly in place. In these drawings,

Figures 1, 2 and 3, respectively, are top, end and side elevations of a two-wire connector embodying my invention.

Fig. 4 shows the preferred screw-bolt and nut partially sectioned.

Figs. 5 and 6, respectively, are top and side elevations of a modified form of test-connector adapted for uniting three or more 50 wires.

Figs. 7 and 8 are similar views of a two-wire connector of another modified type.

Figs. 9 and 10, respectively, are top and end views of the main or body-member of 55 still another modified type, while Figs. 11 and 12, respectively, illustrate two and three-

wire test-connectors, embodying my invention in additional modified forms.

Throughout the several figures of drawings, I have employed the same character of 60 reference, to indicate similar parts.

From an inspection of said drawings, it is apparent that a common body-portion accommodates a plurality of detached washers or clips, each of which secures one or more 65 wires thereto in the same or different planes and thereby mechanically and electrically connects said wires by means of the ample engaging or bearing surfaces afforded for said wires.

The respective structures as herein illustrated, are shown to be of such simple construction that any extended description is superfluous, but I will explain briefly the several types of connector embodying my 75 invention selected and shown herewith. Referring to the first three figures, *a*, the body-portion, is cut from a bar or strip of suitable metal, such as hardened copper, and punched or bored adjacent to either end thereof. 70 Two clips *b* of identical form having over-turned ends positioned adjacent to the edges of the body-portion, *a*, are respectively secured in place above the wires, *c, d*, by means of the bolts and nuts, *e, f*. The heads of 80 said bolts preferably are slotted, and the ends bored out as indicated at *e'*, Fig. 4, so that the threaded end of bolt may be upset or slightly flared to prevent the accidental removal of the nut.

Except for the provision of an additional washer *g*, fitting within a recessed central body-portion *a'*, and secured by the bolt and nut, *e, f*, the test-connector of Figs. 5 and 6 is similar to the one just described. This is 95 depicted as accommodating some four wires; two, *h, i*, being placed transversely beneath the washer *g*, and two, *c, d*, respectively beneath the terminal clips, *b, b*.

In the test-connector of Figs. 7 and 8, the 100 body-portion *a* is provided with upturned edges *a''*, above and below which are accommodated the washers *g* secured thereto by means of the bolts and nuts, *e, f*. A slight modification of this idea finds embodiment 105 in an analogous body-portion, *j*, shown in Figs. 9 and 10, wherein alternately disposed lugs, *j', j''*, extend upon either side thereof for the purpose of embracing the superposed washers and wires, which are not shown in 110 the drawings. Finally, as adequately typifying additional variations of my improved

construction, I may refer to Figs. 11 and 12, wherein the body-portion *a* is bent in different planes for accommodating the washers *g*, and the corresponding wires secured thereunder. On the one hand, the two wires are connected in different planes by the device, while three wires are accommodated in figure last named.

It will be seen that the several clips or washers and their respective connecting body-portions are so constructed, that when assembled, the screw-bolts bring them squarely into contact with the interposed wires, while holding the respective members against turning out of position. The overturned retaining edges provided either upon the clips or body-portions as shown, may, with advantage, be made of different lengths (see particularly Figs. 2, 4, 8 and 10) for the purpose of permitting the wires to be slipped into position, while engaging the edge of the opposing member to prevent the parts from turning out of position. Thus, the overhanging lugs or shoulders provided upon these members, or the suitably shaped body-portions, serve to hold all the parts in alinement, while permitting quick and individual adjustment or release of the connected wires. The clips or washers are so proportioned as to afford relatively large bearing surfaces which will hold the wires securely in place without breaking the hard outer skin thereof.

Preferably, the washers and clips in common with the body-portions, are stamped from hardened copper strips, although other sheet metal blanks may be employed; also the bolts and nuts are best constructed from brass, but of course, these materials and many of the details of form and construction herein specified, comprise no necessary part of my invention.

It will be seen that the test-connectors of my invention permit the independent connection of each wire or wires to be secured under a given clip, so that the lineman may readily adjust the connectors without assistance. Moreover, with these test-connectors, the disconnection of one wire for temporary

testing purposes may be effected, without interfering with any other wire or wires clamped thereon by additional clips, and thus affords a convenient and secure method of connection and disconnection.

With the structures shown, the several wires may be connected in different non-interfering planes and preferably upon opposite sides of the body-portion, when relatively few wires are connected. Down-turned ends of the clips or angularly bent body-portions adjacent to the clips, afford shoulders for alining the members of the test-connector and for retaining the inserted wires in alinement, hence my improved constructions are extremely convenient for their intended use.

I claim as new and desire to secure by Letters-Patent, the following:—

1. A test connector for electric wires comprising a strap-like body-portion, a plurality of retaining-members disposed on opposite sides of the body-member, each retaining-member being formed with a shoulder for constantly alining it with the body-member and being formed with a second shoulder for alining inserted wires, and screw mechanism for adjusting each retaining-member to the body-member individually of any other retaining-member.

2. In a test-connector for electric wires, the combination with an elongated and flattened metallic body portion, of a plurality of flat retaining-members disposed upon opposite sides thereof, associated alining and retaining shoulders respectively bent therefrom and adapted to hold the retaining-members in alinement with the body portion and the wires normally in position, and individual screw-adjusting means for said retaining-members, proportioned to insure the normal engagement of the alining shoulders, substantially as set forth.

In testimony whereof I affix my signature in the presence of two witnesses.

ARTHUR KNEISEL.
